UNITED STATES PATENT OFFICE.

STEPHEN A. GIBSON, OF HEREFORD, ARIZONA.

FASTENING DEVICE FOR STIRRUP-LEATHERS OF SADDLES.

1,212,047.

Specification of Letters Patent.

Patented Jan. 9, 1917.

Application filed February 8, 1916. Serial No. 77,010.

To all whom it may concern:

Be it known that I, STEPHEN A. GIBSON, a citizen of the United States, residing at Hereford, in the county of Cochise and State 5 of Arizona, have invented new and useful Improvements in Fastening Devices for Stirrup-Leathers of Saddles, of which the following is a specification.

This invention relates to improvements in 10 fastening devices for the stirrup leathers of saddles.

At the present time, the stirrup leathers of saddles, particularly the saddles used throughout the West, are held in adjusted 15 position by means of laces. And in order to adjust the stirrups, it is necessary to remove these laces to shorten or lengthen, as the case may be, the stirrup leathers, and then draw the laces through the openings again, thus 20 causing considerable loss of time, incident to the untying of the tie knots in the laces and the rethreading and retying of the laces. Furthermore, these laces rub against the sides of the horse and rot out as a result 25 of the sweating of the horse, thereby necessitating the replacing of the laces. Again, the knots in the laces often slip and become loose, thereby permitting the stirrups to drop down so that one stirrup is lower than 30 the other with the result that the rider is compelled to dismount and readjust the leathers, and it not unfrequently happens that the laces are pulled out under the weight of 35 the rider and the stirrups become detached from the leathers, thereby throwing the rider from the horse.

In carrying out the present invention, it is my purpose to provide a fastening device for stirrup leathers whereby the leathers 40 may be held in adjusted position without the necessity of lacing and which will be unaffected by the sweating of the animal and hold the stirrup in proper position at all times, thereby lessening the possibility of accidents due to the stirrup becoming detached 45 from the leather.

It is also my purpose to provide a device of the class described which may be readily and quickly applied to the stirrup leather 50 and removed therefrom and which will be securely and effectively fastened to the leather so as to prevent accidental detachment of the fastening device from the leather.

With the above and other objects in view, 55 the invention consists in the construction,

combination and arrangement of parts hereinafter set forth in and falling within the scope of the claim.

In the accompanying drawing, Figure 1 is a perspective view showing the stirrup leather equipped with my improved fastening devices. Fig. 2 is a fragmentary sectional view through the leather and fastening devices therein. Fig. 3 is an enlarged collective view showing the parts of one of the fasteners separated.

Referring now to the drawing in detail, 1 designates a portion of a stirrup leather, while 2 indicates a stirrup mounted in the stirrup leather. The usual manner of connecting the plies of the stirrup leather is by means of a lace, and this lace is threaded through openings formed in the plies of the stirrup leather and is designed to hold a stirrup in adjusted position. This method of fastening the plies of the stirrup leather 75 is open to the objections hereinbefore set forth and is decidedly objectionable.

In accordance with my present invention, I eliminate the lace and employ fastening 80 devices 4 as shown in Fig. 2 of the drawing. These fastening devices are identical in construction and each embodies a head 5 having a shank 6 secured to one side thereof at the center of the head and threaded exteriorly, 85 and a disk 7 having a sleeve 8 secured to one side thereof at the center and threaded interiorly. The shank 6 and the sleeve 8 are of substantially the same length and when the shank is threaded into the sleeve the 90 head 5 and the disk 7 are spaced apart a distance equal to the thickness of the plies of the stirrup leather. Formed on the disk 7 at diametrically opposite points and projecting in the same direction as the shank are prongs 95 10 adapted to bite into the inner ply of the stirrup leather when the fastening device is applied thereto. In this embodiment of my invention, I have shown the head 5 as formed with a transverse slot 11.

In practice, the plies of the stirrup leather are adjusted to bring the stirrup to the desired elevation and the sleeves 8 on the disks 7 are passed through the respective alining openings in the plies, the disks 7 being arranged upon the inner side of the plies. The shanks 6 carried by the heads 5 are now threaded onto the respective sleeves 8 and pass into the alining openings and the plies of the leather are clamped between the inner 105 110

surfaces of the disks and the heads, thereby drawing the prongs 10 into the inner ply of the leather. A cord 12 may now be laced through the slots 11, if desired, so as to prevent accidental disconnection of the heads from the disks.

It will be seen that I have provided a fastening device whereby the plies of stirrup leathers may be securely and effectively fastened together to hold the stirrup in adjusted position, thereby eliminating the necessity of employing laces to fasten the plies of the stirrup leather. The disks 7 on the inner ends of the respective fastening devices are arranged adjacent to the sides of the animal and as these disks are formed of metal or other suitable material, the fastening devices are unaffected by the moisture exuding from the sides of the horse. The cords 12 may or may not be employed, this being optional with the rider.

While I have herein shown and described the preferred form of my invention by way of illustration, I wish it to be understood that I do not limit or confine myself to the precise details of construction herein described and delineated, as modification and variation may be made within the scope of

the claim and without departing from the spirit of the invention.

I claim:

The combination with stirrup straps, of fastening means therefor, said means including fastening devices arranged in a double row each of which comprise a member provided with a threaded shank adapted to be passed through the ends of the straps from one side, a second member provided with a threaded sleeve adapted to be passed through the straps upon the opposite side and engaged with said shank, a head upon the shank provided with prongs for engagement with one of the straps, a head formed upon the sleeve and provided with an opening and a single removable flexible element for insertion through all of the said openings, whereby all of the members of the said fastening devices are prevented from turning.

In testimony whereof I affix my signature in presence of two witnesses.

STEPHEN A. GIBSON.
